C. R. MABEE ET AL

DEVICE FOR CONDENSING GASES

Original Filed Feb. 5, 1915

UNITED STATES PATENT OFFICE.

CHARLES R. MABEE AND MAY C. MABEE, OF BUFFALO, NEW YORK.

DEVICE FOR CONDENSING GASES.

Application filed February 5, 1915, Serial No. 6,359. Renewed December 7, 1922.

To all whom it may concern:

Be it known that we, CHARLES R. MABEE and MAY C. MABEE, of the city of Buffalo, county of Erie, and State of New York, have invented certain new and useful Improvements in Devices for Condensing Gases; and we do declare that the following is a full, clear, and exact description of the same.

10 This invention relates to a condensing apparatus, and while designed more particularly for the condensing of steam, is equally applicable for the condensing of various gases.

15 It is one of the purposes of the invention to provide an apparatus of the character stated in which the steam or gas to be condensed is brought into contact with a surface or surfaces, which surfaces are adapted 20 to have transmitted thereto a cooling temperature through the medium of a cooling fluid adapted to move over said surfaces subjected to the heat from the gas to be condensed.

25 Another feature of the invention is to provide novel means for imparting the necessary movement to the cooling medium in order to secure more uniform circulation thereof, and whereby to more readily and effectively condense the gases as they contact 30 with the reverse side of the surface or surfaces subjected to the cooling medium.

In carrying out the invention it is proposed to provide a plurality of concentrically 35 arranged annular steam or gas chests or spaces arranged in alternate relation with an annular series of spaces for the reception of a cooling medium, together with means for properly circulating said cooling medium.

More particularly the invention includes an apparatus of the character above described, involving a fewer number of parts, simpler in design and construction, more compact, less expensive to produce and more efficient in operation than prior apparatus or devices heretofore employed and at present in use for like purposes.

Still further, the invention contemplates 50 an arrangement of the temperature treating surfaces in as compact a form as possible, conducive to securing rapid movement or circulation of the cooling fluid over the treating surfaces with an economical expenditure 55 of the power employed.

Again, it is contemplated to so construct and arrange many of the parts that they may be detached and removed at will for the purpose of cleansing, repairing or replacement of parts, etc., as may be desired.

Still other and further improvements, advantages, and novel details in the construction and arrangement of the various parts of the invention will be appreciated from the description to follow, which for a clear understanding of the invention is to be considered in connection with the accompanying drawings which form a part hereof, and wherein is disclosed for the purpose of illustration, a convenient and satisfactory embodiment of the invention.

In the drawings, Fig. 1 is a vertical cross section of our improved device.

Fig. 2 is a cross section of the same, substantially on the line 2-2 of Fig. 1.

With more particular reference to the drawings wherein like reference numerals refer to corresponding parts throughout the several views, a container is provided, the same being substantially of cylindrical form 80 and arranged upright. The said container comprises a cylindrical side wall (1), a bottom wall (2), and a dome-shaped top wall (3), the top wall (3) and side wall (1) conveniently having abutting outwardly projecting annular flanges (4) secured to one another as by removable bolts or the like (5). The container as just described constitutes a substantially closed gas-tight vessel, but as has been appreciated, by removing the bolts 90 (5) the top or head of the container may be removed to afford access to the interior of the body portion thereof. Leading from any suitable source of steam supply is a suitable conduit (6) connecting with the top wall (3) 95 at substantially the center thereof, whereby to deliver to the interior of the container the steam or other gas to be condensed.

Mounted upon the side wall (1) of the container adjacent the top thereof is a suitable support (7) the same being conveniently secured in any desired manner as through the medium of an annular angle connection (8) secured respectively to said support (7) and the side wall (1) of the container. Said support (7) is further braced and supported preferably through the medium of one or more rods, two being illustrated at (9) as projecting upwardly from the support (7) 105 and secured in any desired manner to the top 110

wall (3) of the container as by passing through apertures in said wall and retained in place by suitable nuts (10).

Depending from said support (7) which conveniently takes the form of an angle bar, are a concentric series of annular walls (11), which said walls are corrugated circumferentially and form alternate steam chests (12) and water spaces (13). The adjacent walls forming the steam chests are connected to form a closed bottom or lower end (14) which lower ends have an annular flange or extension (15) projecting inwardly beyond the inner wall of each steam chest. The steam chests are open at the top so as to be in open communication with the chamber formed by the dome or top (3) of the container, which latter as has been described is in communication with the steam inlet (6) of the container. The walls surrounding the annular water spaces (13) are connected to form a closed top and separated from one another to form an open bottom as clearly illustrated in Fig. 1 of the drawings.

The annular series of steam chests formed by the walls (11) as above described are of gradually increasing lengths from the center steam chest to the outer steam chest of said annular series; that is to say, the annular steam chest next adjacent to and surrounding the central steam chamber projects below the lower end of the central chamber, and so on throughout the series.

The cooling medium for transmitting the cooling temperature to the walls surrounding the steam chests, which cooling medium conveniently takes the form of water, is preferably introduced through one or more conduits (16) projecting through the top wall (3) and having vertically disposed offset pipes (17) communicating one with each of the water spaces (13). A suitable control valve (18) is provided for regulating the supply of water introduced into the water spaces, or to entirely shut off the passage of water through the conduit (16), as desired. A suitable stuffing-box (19) is provided for effectively closing the opening in the wall of the container for the reception of the conduit (16). Also connecting with the water conduit (16) is an auxiliary conduit or by-pass (20) connecting with an annular pipe or conduit (21), surrounding the steam inlet (6) and having in the lower surface thereof a series of outlets so as to deliver in the form of fine jets or sprays, a given quantity of water to form upon the exterior wall of the container a film of water. This auxiliary conduit (20) is controlled by a suitable valve (22).

In order to take off the water as formed within the steam chests, we preferably provide a vertically disposed pipe (23) in each

steam chest, said pipe projecting to a point adjacent the lower end of said chests and being open at this point. The pipes (23) at the top thereof connect with a horizontally disposed offtake pipe or conduit (24) projecting through the top wall (3) of the container and controlled by a suitable valve (25).

In order to impart the necessary circulation to the cooling fluid, we provide a series of vertically spaced horizontally disposed rotors (26), said rotors being of preferably hexagonal shape and having flat upper and lower surfaces as indicated in dotted lines in Fig. 2. Said rotors (26) are of increasing diameters from the topmost to the lowermost one in the vertical series, there being a rotor for each water space.

The means for imparting rotatable movement to the rotors preferably takes the form of a steam turbine (27) mounted upon the base of the container, the turbine being of any approved type and having a steam inlet pipe (28) with a valve (29) for regulating the admission of steam for action upon the movable part of the turbine. The turbine is adapted to impart rotatable movement to a suitable shaft (30) projecting through the bottom of the wall of the container and connected to the rotors (26) in any convenient manner. The exhaust steam from the turbine is conveniently discharged through the conduit (31) into the steam chamber or reservoir at a point adjacent the top of the container.

The rotatable shaft (30) has an upwardly extending part adapted for connection with suitable fan blades (32) which in the rotatable movement of the shaft are adapted to diffuse the gas to be condensed as it enters the interior of the container, and also to direct said gas in a downward and outward direction whereby to effectually circulate the gas in the annular steam spaces (12).

A vacuum gauge (33) is provided, the same being connected conveniently to the top wall (3) of the container and in communication with the interior, and likewise said top wall may be provided with one or more sight openings (34) as desired.

An inclined trough or collar (35) is supported by braces (36) upon the cylindrical wall (1) of the container at a point adjacent to and below the abutting flanges of the top and side wall of the container whereby to receive the water as it trickles downwardly from the outer surface of the top wall over said flanges. The trough at its base does not have a snug fit with the peripheral wall 1 of the container whereby to permit of the discharge of water from the trough and guide the water again into contact with the outer surface of the container. Arranged at the base of the con-

tainer below the trough is a suitable annular trough (37) adapted to receive the water as it flows downwardly over the outer surface of the cylindrical wall of the container, 5 a discharge conduit (38) being provided for said trough.

Arranged in communication with one of the water spaces of the container is a suitable conduit (39) having a valve-control 10 (40) whereby to permit regulation of the discharge of the cooling fluid from the container.

The operation is substantially as follows: The gas or vapor to be condensed is introduced into the container through the inlet conduit (6) where it is subjected to the diffusing blade (32) and passes into the various annular steam chests where it is delivered into contact with the cooling surfaces (11) which causes the steam to condense and pass down to the lower extremity of the annular steam chests from whence it is withdrawn through the pipes to any suitable receptacle or place of deposit.

25. The valve (29) being open, and the turbine set in motion, there is imparted rotatable movement to the diffusing element just referred to and also rotatable movement at a high velocity of the rotors (26), 30 thereby forcing the cooling water outward and in a circular path around and against the walls of the annular steam chests on the outer surfaces thereof. The rotors (26) tend to project the cooling water outward in 35 a rotary path, and the pressure of the cooling fluid against the outer walls of the steam chest together with the rapid movement of the cooling fluid, causes transmission of temperature through the cooling 40 walls or surfaces in proportion to the velocity of the cooling fluid and the pressure exerted against said surfaces. The rate of travel of the cooling fluid in the present apparatus is considerably greater than in 45 other known apparatus for similar purposes.

It has been seen that the inlet for the water at the top of the container is valve controlled with the result that the supply of water may be entirely shut off if desired, 50 or regulated to a nicety. This is also true with regard to the outlet for the water at the base of the container. Assuming that both valves are open, the water will descend over the walls of the annular steam chambers and find an exit through the outlet conduit 39. After a supply of water has been introduced into the annular spaces surrounding the steam chambers, both valves, 55 may, if desired, be closed, in which event assuming that the rotors 26 are placed in operation, the water will be rapidly circulated in a circular path, and have an upward tendency, somewhat after the manner of centrifugal machines having an inlet at 60 the base and an agitator which forces the

liquid upwardly to a discharge opening at the top. As the water becomes heated, the discharge valve 40 may be opened, and the inlet valve may likewise be opened, whereby to permit of the escape of the heated water, 70 and the admission of the cooler water.

Preferably the valve (22) in the auxiliary conduit or by-pass (20) is regulated in such a way as to permit a desirable portion of the cooling fluid to flow out of the openings 75 formed in the annular pipe or ring surrounding the steam inlet (6), said cooling fluid passing over the exterior surfaces of the dome-shaped top of the container and the exterior surface of the cylindrical side-wall (1) of the container thereby acting as an auxiliary to the cooling fluid surfaces within the container or condenser and thereby increasing its capacity to condense gases and also obviate the necessity of a larger apparatus to accomplish a given amount of work. This cooling water passes over the external surface of the container in the form of a thin film substantially covering 80 said surface.

90. The rotors (26) are so arranged and positioned with regard to the lower extremities of the steam chests as to cause the cooling fluid to take on a circumferential motion in each of the series of spaces provided for the circulation of said cooling fluid. Each annular space for the cooling water is provided with a rotor for the circulation of said cooling water and as has been seen, the diameters of the rotors differ in proportion to the diameters of the steam chests and water spaces. The annular inward projections at the lower ends of the steam chests tend to form abutments which cooperate with the rotors to resist downward 95 motion of the cooling fluid.

100. By reason of the peculiar shape, preferably hexagonal, of the rotors, the same tend to propel and project the cooling fluid in an outward direction, thereby making the 110 centrifugal motion more pronounced.

Means other than the steam turbine (27) may be provided if desired for imparting the necessary rotatable movement to shaft (30) and associated parts, though the turbine is 115 preferred in this connection.

120. The walls forming and separating the water and steam spaces are preferably formed of copper or other suitable metal capable of rapidly transmitting temperatures, and by reason of the corrugations formed in the metallic walls, the total area of the surfaces is increased, and at the same time the metal is reinforced.

125. It may be desirable at times to introduce the cooling water through the conduit (39) instead of the conduit (16), and this alternative operation may be made without the necessity of material changes in the structures as illustrated. Likewise if desired, the 130

container may be arranged horizontally instead of vertically as illustrated and described, in which event obvious modifications of the means for applying to the exterior 5 surface of the container the film of cooling fluid may be resorted to.

What we claim is:

1. In an upright surface condenser, the combination of a cylindrical container, a plurality of annular steam chests mounted therein and separated to form therebetween a plurality of annular spaces, means for introducing a cooling fluid between the exterior surfaces of said annular steam chests, 10 and connected rotors operatively associated one with each of said spaces whereby to circulate the cooling fluid over the surfaces of the steam chests.
2. In a condenser, the combination of a container, a plurality of concentrically arranged annular steam chests mounted therein and separated to form a plurality of spaces between said steam chests, means for delivering gas to be condensed into said steam chests, means for delivering a cooling fluid into said spaces between the steam chests, an independent rotor for each space, whereby to impart to the cooling fluid circumferential and endwise movement in said spaces, and means for withdrawing the products of condensation from the steam chests.
3. In a condenser, the combination of a vertically disposed container having therein a concentric series of annular gas or steam chests, and alternately arranged annular fluid cooling chambers, and independent means operatively positioned with respect to each of said cooling fluid spaces whereby to impart to the cooling fluid in each of said spaces circumferential movement.
4. In a condenser, the combination of a vertically disposed container having therein a concentric series of annular gas or steam chests, and alternately arranged annular fluid cooling chambers, independent means operatively positioned with respect to each of said cooling fluid spaces, and means for rotating the said last-mentioned means 50 at a high speed whereby the cooling fluid will be circulated lengthwise as well as circumferentially over the walls of the steam chests.
5. In a condenser, the combination of a cylindrical container, a series of annular steam chests concentrically disposed within the container and separated from one another to form a series of cooling spaces, a plurality of rotors of different diameters, 55 one for each of said cooling spaces, a turbine exterior of said container connected with said rotors, and an exhaust pipe adapted to convey the exhaust steam from the turbine to a point in communication with the steam chests.

6. In a condenser, the combination of a container, a plurality of separated concentrically arranged annular steam chests within the container, the lower edges of said chests being arranged in different vertical 70 planes, means for introducing a cooling medium into the container and a series of rotors of different diameters at the lower edge of the chests adapted to circulate the cooling fluid in the spaces between the steam chests. 75

7. In a condenser the combination of a vertically disposed cylindrical container having therewithin a plurality of separated concentrically arranged annular steam chests, means for introducing steam to said chests at the top thereof, outlet pipes from said chests, means for introducing a cooling fluid to the container and rotors in operative association with each space between the steam chests whereby to circulate said cooling fluid through said spaces. 80

8. In a condenser, the combination of a vertically disposed cylindrical container having therein a plurality of separated concentrically arranged annular steam chests 85 of variable lengths, said chests forming therebetween annular cooling fluid spaces, spaced rotors of different diameters, one for each cooling fluid space and in operative position to circulate the cooling fluid circumferentially over the walls of the chests and a turbine connected with the container for imparting movement to the rotors.

9. In an apparatus of the character described, the combination of a vertically disposed container having a steam inlet and an inlet for water or the like, walls within the container dividing the same into a series of annular steam chests and water spaces arranged in alternate relation with one another, rotors within the container for circulating the water through the water chambers, and connected rotatable means for diffusing the gas through the steam chests as introduced into the container. 100

10. In a condenser, the combination of a vertically disposed substantially cylindrical container having therewithin a plurality of concentrically arranged annular steam chests separated from one another by annular water spaces, said container having a substantially central opening in the top thereof for the introduction of steam or the like, said opening being in communication with an open end of the steam chests, a water conduit projecting through one wall of the container and adapted to discharge water into the water spaces between the steam chests, an auxiliary conduit leading from the water conduit and adapted to discharge water upon the exterior wall of the container, and a plurality of rotors, one for each of the water chambers adapted to circulate the water endwise as well as circumferentially over the wall of said steam chests. 115

11. In a condenser, the combination of a cylindrical container, a plurality of annular chests mounted therein and separated to form therebetween a plurality of annular spaces, means for introducing a fluid between the exterior surfaces of said annular chests, and connected rotors operatively associated one with each of said spaces whereby to circulate the fluid over the surfaces of the said chests.

12. In a condenser, the combination of a container, a plurality of concentrically arranged annular chests mounted therein, and separated to form a plurality of spaces between said chests, means for delivering ma-

terial into said chests, means for delivering fluid into said spaces between the chests, an independent rotor for each space whereby to impart to the fluid circumferential and endwise movement in said spaces, and means for withdrawing material from the said chests.

Signed at Toronto, in the county of York, in the Province of Ontario, in the Dominion of Canada, this fourth day of February, 1915.
